US00D756523S

(12) **United States Design Patent**
Tsai et al.

(10) **Patent No.:** US D756,523 S
(45) **Date of Patent:** ** May 17, 2016

(54) **DOCKING STATION OF REMOTE MEDICAL SYSTEM**

(71) Applicant: **Quanta Computer Inc.**, Taoyuan Shien (TW)

(72) Inventors: **Po-Chih Tsai**, Tainan (TW); **Ting-Han Huang**, Taichung (TW); **Kang-Wen Lin**, New Taipei (TW); **Chia-Yuan Chang**, Taichung (TW)

(73) Assignee: **QUANTA COMPUTER INC.**, Guishan Dist., Taoyuan (TW)

(**) Term: **14 Years**

(21) Appl. No.: **29/458,662**

(22) Filed: **Jun. 21, 2013**

(30) **Foreign Application Priority Data**

May 3, 2013 (TW) 102303148

(57) **CLAIM**

The ornamental design for a docking station of remote medical system, as shown and described.

DESCRIPTION

FIG. 1 is a perspective view of a docking station of remote medical system showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are for environmental purposes only and form no part of the claimed design.
